United States Patent Office

Des. 183,108
Patented June 24, 1958

183,108

AIRCRAFT

Nathan C. Price, Mexico City, Mexico

Application June 11, 1956, Serial No. 41,846

Term of patent 14 years

(Cl. D71—1)

FIG. 1

FIG. 2

FIG. 1

FIG. 2

FIG. 3

Figure 1 is a side elevational view of an aircraft embodying my new design;

Figure 2 is a top plan view thereof;

Figure 3 is a bottom plan view thereof;

Figure 4 is a front elevational view thereof; and

Figure 5 is a rear elevational view thereof.

The dominant features of my design reside in those portions shown in full lines.

I claim:

The ornamental design for an aircraft, as shown and described.
